SUCTION CLEANER

Charles G. Troxler, North Canton, Ohio, assignor
to The Hoover Company, North Canton, Ohio,
a corporation of Ohio

Application October 20, 1937, Serial No. 169,945

11 Claims. (Cl. 15—6)

The present invention relates to suction cleaners in general, and particularly to improvements to be embodied in a suction cleaner which reduces the over-all height of the cleaner.

It is an object of the invention to provide a new and improved suction cleaner. It is another object of the invention to provide means for arranging the motor and fan chamber side by side and parallel with the cleaner nozzle to reduce the over-all height of the cleaner. Another object is to provide an air passage extending rearwardly from the nozzle along the upper wall of the cleaner body to the fan chamber. A further object is to provide means at the top of the cleaner body for converting the machine from an "on the floor" cleaner to a machine adapted to create suction for use with dusting tools in "off the floor" cleaning. Another object is to provide a ball-less connection between the handle and cleaner body, whereby when the handle is in low operating position it lies in the plane of the top wall of the cleaner to permit operation of the cleaner under furniture having low floor clearance. Other objects and advantages of the invention will appear in the specification and drawings wherein:

Fig. 1 is a perspective view of the suction cleaner;

Fig. 2 is a section along the line 2—2 of Fig. 3;

Fig. 3 is a bottom view of the cleaner;

Fig. 4 is a section along the line 4—4 of Fig. 3;

Fig. 5 is a section along the line 5—5 of Fig. 3;

Fig. 6 is a sectional view showing a dusting tool attached to the top of the cleaner.

The suction cleaner herein disclosed comprises a casing 10 having a flat top wall 11 curved downwardly at its forward end to form a nozzle 12 provided with front and rear surface contacting lips 13 and 14, respectively. Supporting the casing 10 is a base or frame 15 having a top wall 16 from which upstands an arcuate wall 17 having its upper end nested in an arcuate recess 18 defined in the casing 10 to support the latter.

An air passageway 20 extends upwardly and rearwardly from the nozzle lips as shown in Figure 4 and rearwardly along the right side of the cleaner as viewed in Figure 5 and terminates at the fan eye 22 in the top wall 16 of the base 15. The air passageway is defined at its top by the top wall 11 of the casing 10, and at its bottom by the top wall 16 of the casing 10. The bottom wall 18 of the air passageway 20 extends upwardly and rearwardly from the rear nozzle lip 14 as indicated at 25 and then in a horizontal plane as shown at 26 to the fan eye 22. The sides of the

air passageway 20 is defined by the arcuate wall 17 which has a semi-circular portion 27 outlining the rear end of the air passageway adjacent the fan eye 22, and then extends forwardly and is flared outwardly as shown at 29 to the rear nozzle lip 14, the projecting height of the side wall 17 being gradually reduced as outlined at 30 to gradually merge into the surface of the downwardly curved portion of the bottom wall 18 of the air passageway.

Included in the base 15 is a fan chamber 35 defined at its top by the top wall 16 of the base 15 and at its sides by an arcuate wall 36 depending from the top wall 16. The side wall 36 has a substantially circular portion 34 and diverges towards the rear of the base 15, as indicated at 31, to form the side walls 38 of the exhaust passage 39 which terminates at 40 along the central longitudinal axis of the cleaner. The bottom of the fan chamber 35 is closed by a plate 41 provided with a marginal recess 42 to receive the lower edge 43 of the fan chamber wall 36 and a flange 44 depending from the lower wall 45 of the base 15 defining the outlet of the exhaust passageway 39.

A plurality of screws 46 are provided to removably secure the bottom plate 41 to the fan chamber side wall 36. The plate 41 is formed with a cylindrical seat 50 which serves to support the fan shaft bearing 51. Secured to the plate 41 by means of rivets 52 is a pressed metal member 53 which houses the remaining portion of the fan shaft bearing 51. Carried by the bearing 51 is a vertically mounted fan shaft 54 to which is attached a suction creating fan 55 comprising spaced blades 56 mounted upon the fan back 57. The back of the fan is provided with a peripheral depending flange 58 which extends into a circular channel 59 formed in the plate 41 to prevent leakage of dirt-laden air into the bearing 51. The hub portion 60 of the fan is dish shaped, as indicated at 61, to accommodate the bearing 51 to thereby aid in reducing the over-all height of the cleaner.

Supported on the fan shaft 54 is a pulley 62 for a belt 63 extending through an opening 64 in the wall of the air passageway 20 and is arranged in an annular recess 65 in an agitator 66 mounted in the nozzle 12 for contacting the surface undergoing cleaning. Enclosing the belt 63 is a housing 67 having a unitary top wall 68 and side walls 69 secured by the rivets 52 to the plate 41 and to the rear wall of the air passageway 20 by means of screws 70. The bottom wall 71 is secured to the housing side walls 69 and to the

rear wall of the air passageway 28 by means of screws 72. The belt housing plate 71 is provided with an annular flange 73 defining an opening for the fan shaft 54, and is disposed in a circular recess 75 in the pulley 62 to prevent leakage of dirt-laden air from the belt housing 67.

Integral with the casing 10 is a motor housing 88 arranged alongside the fan chamber 35 so that the latter and the motor housing 88 are disposed parallel to the nozzle 12 of the cleaner. The motor housing is defined at its top by the top wall 11 of the casing 10 and at its sides by a wall 81 depending from the top wall 11 of the casing 10. The bottom of the housing is closed by a plate 82 removably secured by screws 83 to the housing side walls 81.

Disposed in the motor housing 88 is a vertically mounted motor 85, the motor field 86 surrounding the rotating armature 87 carried by a shaft 88 on which is secured a commutator 88. The opposite ends of the motor shaft 88 are journalled in bearings 89 carried in casings 91 containing a lubricant absorbing and retaining material 92. The container 91 at the upper end of the motor shaft is arranged in a chamber formed by an annular flange 94 depending from the top wall 11 of the casing 10 and is held therein by a plate 95 secured by screws 96 to the flange 94, while the container 91 at the lower end of the motor shaft is disposed in a chamber in the bottom plate 82 and is removably held therein by a spring ring 98.

In order to cool the motor 85 a motor cooling fan 100 is mounted on the motor shaft 88 and is arranged in a fan chamber 101 formed in the bottom plate 82 which is provided with opening 102 communicating with the atmosphere. Operation of the motor rotates the cooling fan 100 which functions to cool the motor 85 by drawing air into the housing 88 through an opening 99 and then passes through the circular opening 103 in the false bottom plate 104 into the fan chamber 101 and exhausts through the opening 102.

The suction creating fan 55 is driven by means of a belt 105 extending transversely of the cleaner from the motor pulley 106 mounted on the motor shaft 88 to a fan pulley 107 secured to the lower end of the fan shaft 54. A belt housing encloses the belt 105 and comprises a top plate 108 forming part of the bottom plate 71 of the agitator belt housing 67, and has a U-shaped bottom plate 110 secured by screws 111 to the top plate 109.

The dust bag 112 is secured to the exhaust outlet 40 and is suspended at its upper end, not shown, from a hollow handle 113. The lower end of the handle is disposed in a socket 114 pivotally mounted on a pin 115 supported in a pair of brackets 116 upstanding from the top wall 16 of the base member 15. These brackets are arranged at the rearmost end of the cleaner and are enclosed in a chamber 117 defined between the top walls 11 and 16 respectively of the casing 10 and the base member 15, to thereby provide an uninterrupted smooth surface along the top of the cleaner. Handle position controlling means are provided in the chamber 117 and comprises an arcuate sector 118 carried by the handle 113. The arcuate edge of the sector is provided with suitable seats 119 which are adapted to be contacted by a leaf spring 120 mounted on the top wall 16 by rivets 121. The front of the cleaner is movably supported by a pair of wheels 122 carried on a crank shaft 123 controlled by the adjusting

means indicated generally by the reference character 124 to raise or lower the nozzle lips relatively to the surface covering. A pair of rear wheels 125 support the rear end of the cleaner and are journalled on a pin 126 carried in a bracket 127 secured by rivets 128 to the bottom plate 41 of the exhaust passageway 39.

In order to make possible the use of the cleaner for the cleaning of drapes, curtains, etc., the top wall 11 of the casing 10 is provided with a circular opening 130 communicating with the air passageway 28 and is arranged opposite the eye 22 of the fan chamber 35. The opening 130 is covered by a cover plate 131 having a plurality of spring locks 133 adapted to engage the defining edge 134 of the opening to lock the cover plate in position. As shown in Figure 5 the cover plate 131 extends along the top of the casing beyond the opening 130 to balance the appearance of the cleaner and is provided with a lug 135 adapted to be disposed in an opening in the casing to properly position the cover on the cleaner. When the cover plate 131 is removed a converter 137 of a dusting tool unit can be inserted through the opening 130 to seat in the eye 22 of the fan chamber, as indicated in Fig. 6, a suitable spring clamp 138 being provided on the converter to engage the edge 134 of the opening 130 locking the converter in position.

In operation, upon supplying current to the motor 85 the motor shaft 88 is rotated causing the belt 105 to rotate the fan shaft 54 and the pulley 62 which in turn rotates the agitator 66 through the belt 63. Operation of the fan 55 creates suction and causes dirt-laden air to enter the nozzle 12 and through the air passageway 28 and enters the inlet 22 into the fan chamber 35 and is discharged through the exhaust passageway 39 into the dust bag 112. The machine is propelled over the surface covering by the handle 113 and when it is desired to clean under furniture having low floor clearance the handle is shifted to the position shown in Fig. 4 into the plane of the top wall 11 of the cleaner to provide a flat surface along the top of the cleaner.

When it is desired to convert the machine for "off the floor cleaning" to clean drapes, cushions and so forth the nozzle adjusting means 124 is manipulated to raise the nozzle 12 and agitator 66 out of contact with the surface covering. The cover plate 131 is removed and the dusting tool converter 137 is inserted through the opening 130 into the eye 22 of the fan chamber 35, and the suction created by the fan 55 is effective to draw dirt laden air through the dusting tool and to discharge it into the dust bag 112.

From the foregoing it will be perceived that I have provided a suction cleaner of low over-all height whereby the machine may be operated under furniture having low floor clearance.

I claim:

1. A suction cleaner, comprising a cleaner body having an elongated nozzle in its forward end, said body having a flat top wall extending substantially horizontally from said nozzle to the rear end of said body, a substantially horizontal fan chamber, a fan in said fan chamber, a suction passage extending upwardly and then horizontally rearwardly from said nozzle to said fan chamber, the top wall of said suction passage being defined by said top wall of said cleaner body and the bottom wall of said suction passage by the top wall of said fan chamber, and a substantially vertically mounted motor for driving said

fan, said fan chamber and motor lying side by side and substantially parallel to said nozzle.

2. A suction cleaner, comprising a cleaner body having a nozzle at its forward end, said body having a flat top wall extending substantially horizontally from said nozzle to the rear of said body, a substantially horizontal fan chamber in said body, a fan in said chamber, a motor below said top wall for operating said fan, a suction passage extending upwardly and then horizontally rearwardly from said nozzle and terminating above said fan chamber, said top wall of said body defining the top wall of said suction passage, said fan chamber and motor lying side by side, the highest point at said terminal end of said suction passage and motor lying substantially in the same horizontal plane, and means in said flat top wall for defining an opening communicating with said suction passage adapted to receive a dusting tool unit.

3. A suction cleaner, comprising a cleaner body having a nozzle at its forward end, said body having a flat top wall extending substantially horizontally from said nozzle to the rear of said body, a substantially horizontal fan chamber, a fan in said chamber, a suction passage extending upwardly and horizontally rearwardly from said nozzle and terminating above said fan chamber, the top wall of said body defining the top wall of said suction passage, and a motor depending below said top wall for operating said fan.

4. A suction cleaner, comprising a base member, a fan chamber and exhaust passage in said base member, a fan in said chamber, a casing covering said base member, a motor housing depending from said casing and disposed alongside said fan chamber, a motor in said housing for operating said fan, means in said base member and casing cooperating to form a suction passage and nozzle, the top wall of said casing defining the top wall of said suction passage, and means in said casing top wall defining an opening communicating with said suction passage and adapted to receive a dusting tool unit.

5. A suction cleaner, comprising a base member, an exhaust passage in said base member, a substantially horizontal fan chamber in said base member, a substantially vertically mounted fan in said chamber, a casing covering said base member, a motor housing depending from said casing, a substantially vertically mounted motor in said housing for operating said fan, and means in said base member and casing cooperating to define a suction passage and nozzle, said nozzle extending transversely of said cleaner, said fan chamber and motor housing lying side by side and substantially parallel to said nozzle.

6. A suction cleaner, comprising a base member, an exhaust passage in said base member, a fan chamber in said base member, a fan in said chamber, a casing covering said base member, a motor housing depending from said casing and disposed alongside said fan chamber, a motor in said housing for operating said fan, a suction nozzle, and a suction passage formed by said

base member and casing for communication between said nozzle and fan chamber.

7. A suction cleaner, comprising a nozzle, a fan chamber, a fan rotating in a substantially horizontal plane in said chamber, a motor housing, said fan chamber and motor housing being disposed side by side transversely of said cleaner, a motor in said housing for operating said fan, means defining a suction passageway between said nozzle and fan chamber, the top wall of said passageway means forming the top wall of said cleaner, and means in said top wall defining an opening communicating with said suction passageway opposite the eye of said fan and adapted to receive a dusting tool for off-the-floor cleaning.

8. A suction cleaner, comprising a base member, a casing covering said base member, nozzle forming means, said casing having a flat top wall extending substantially horizontally from said nozzle means to the rear of said cleaner, means depending from said top wall of said casing and forming a chamber, means in said base member forming another chamber, a fan and a motor for operating said fan, said fan and motor being disposed each in one of said chambers, means forming a suction passageway between said nozzle forming means and the chamber accommodating said fan, said top wall of said casing defining the top wall of said suction passageway, and means in said flat top casing wall for defining an opening communicating with said suction passageway adapted to receive a dusting tool unit.

9. A suction cleaner, comprising a base member, a casing embracing said base member, means depending from the top of said casing and forming a chamber, means in said base member forming another chamber, said chambers being arranged side by side, a fan and a motor for operating the same, said fan and motor being disposed each in one of said chambers below said casing, means forming a suction nozzle, and means forming a suction passageway between said nozzle and the chamber accommodating said fan.

10. A suction cleaner, comprising a base member, a fan chamber in said base member, a fan in said base member, a casing embracing said base member, a motor housing depending from said casing, a motor in said housing for operating said fan, a suction nozzle, and means forming a suction passageway between said nozzle and fan chamber.

11. In a suction cleaner, comprising a nozzle, an agitator in said nozzle, a fan chamber, a fan in said chamber, a suction passageway extending from said nozzle to the eye of said fan chamber, a motor, said motor and fan chamber being disposed side by side, and drive means arranged beneath said motor and fan chamber and adjacent the closed side of the latter, and including means between said motor and said fan to rotate the latter and means from said fan to said agitator to rotate said agitator.

CHARLES G. TROXLER.
